(57) **CLAIM**

The ornamental design for a clamshell food container with double lids, as shown and described.

DESCRIPTION

FIG. 1 is a top, front, and left side perspective view of a clamshell food container with double lids showing my new design with the double lids in a closed position;

FIG. 2 is a top plan view thereof;

FIG. 3 is a bottom view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top, front, and left side perspective view of the clamshell food container with double lids showing the double lids in an open position;

FIG. 9 is a top plan view thereof;

FIG. 10 is a bottom view thereof;

FIG. 11 is a front elevational view thereof;

FIG. 12 is a rear elevational view thereof;

FIG. 13 is a left side elevational view thereof; and,

FIG. 14 is a right side elevational view thereof.

The broken lines illustrate portions of the clamshell food container with double lids which form no part of the claimed design.
